Primary Examiner — Philip S Hyder*Assistant Examiner* — Keith Frank(74) *Attorney, Agent, or Firm* — Terence P. O'Brien(57) **CLAIM**

We claim the ornamental design for a frame of a treadmill, as shown and described.

DESCRIPTION

FIG. 1 is a side, front perspective view of a frame of a treadmill;

FIG. 2 is a first side view of the frame of a treadmill of FIG. 1;

FIG. 3 is a second side view of the frame of a treadmill of FIG. 1;

FIG. 4 is a front view of the frame of a treadmill of FIG. 1; FIG. 5 is a rear view of the frame of a treadmill of FIG. 1; and, FIG. 6 is a top view of the frame of a treadmill of FIG. 1.

The ornamental design that is claimed is shown in solid lines in the drawings. The broken (dashed) lines shown in the figures are included for the purpose of illustrating environmental elements only and form no part of the claimed design.
